(57) CLAIM

The ornamental design for a shoe, as shown and described.

DESCRIPTION

FIG. 1 is a front perspective view of a shoe showing my new design;

FIG. 2 is a side view thereof;

FIG. 3 is a top view thereof;

FIG. 4 is an opposite side view thereof; and,

FIG. 5 is an opposite side front perspective view thereof. The broken lines immediately adjacent to the shaded area define the bounds of the claimed design and form no part thereof. Within the shaded areas, the six circular regions, the four rectangular regions, and the two trapezoidal regions respectively represent eyelets, lace loops, and unclaimed regions of the eyestays and form no part of the claimed design. The broken lines depicting the remainder of the shoe form no part of the claimed design.
